AIR CIRCULATING MEANS FOR BUILDINGS

Otis D. Inscoe, Oxford, N.C.

Application July 19, 1957, Serial No. 672,957

4 Claims. (Cl. 98—34)

2

This invention relates to means for automatically controlling the heat within an edifice, building, barn or other similar structures, to insure uniformity of heat distribution therein.

One of the primary objects of this invention is to provide means actuated by natural phenomena for automatically effecting the substantially equal distribution of heated air within a tobacco curing barn to maintain a uniform temperature therein.

Another object of this invention is to provide wind driven ventilating means for a tobacco curing barn, the means including apparatus for directing an air current within the barn in direct opposition to the direction of the wind.

A further object of this invention is to provide a windmill type of device for driving air circulation means within a building, barn or other edifice, the air circulating means being automatically controlled by the windmill device so as to direct an air current toward that side of the building, barn or edifice, against which the wind directly impinges.

This invention contemplates, as a still further object thereof, the provision of a device of the type generally referred to above which is non-complex in construction and assembly, inexpensive to manufacture, and durable in use.

Other and further objects and advantages of the present invention will become more evident from a consideration of the following specification when read in conjunction with the annexed drawings, in which:

Figure 1 is a front elevational view of a wind driven ventilating means for automatically directing an air current within an edifice in a predetermined direction, the wind driven apparatus being constructed in accordance with the teachings of this invention;

Figure 2 is a side elevational view of the wind driven air circulating apparatus illustrated in Figure 1, Figure 2 being partly in vertical cross-section;

Figure 3 is an enlarged, detailed, fragmentary, cross-sectional view of the wind driving means, together with its power take-off shaft;

Figure 4 is an enlarged, fragmentary, detailed, cross-sectional view, taken substantially on the vertical plane of line 4—4 of Figure 3, looking in the direction of the arrows;

Figure 5 is an enlarged, detailed, cross-sectional view taken substantially on the horizontal plane of line 5—5 of Figure 3, looking in the direction of the arrows; and

Figure 6 is an enlarged, detailed, cross-sectional view taken substantially on the horizontal plane of line 6—6 of Figure 3, looking in the direction of the arrows.

Referring now more specifically to the drawings, reference numeral 10 designates, in general, a wind driven, air circulating device, constructed in accordance with

10 this invention. As illustrated therein, the device 10 is broadly seen to comprise a wind driven impeller 12 mounted on the roof 14 of a barn 16 or other similar edifice, the impeller 12 being connected through suitable driving means with a second impeller 18 mounted for rotation within a rotatable plenum chamber 20 supported within the barn or edifice 16.

15 The impeller 12 includes a hub 22 from which radiates a plurality of spokes 24 to the outer ends of which is fixedly secured a substantially hollow cylindrical drum 26. A plurality of radially spaced impeller blades 28 are hingedly connected at 30 (see Figures 3 and 4) to the drum 26. As is seen in the drawings, the two outer spaced portions 32, 34 of the hinge barrel for each impeller blade are secured to the circumference of the drum 26. The inner end of each impeller blade is fixedly secured to an intermediate hinge barrel portion 36, the latter being disposed intermediate the hinge barrel portions 32, 34 with their respective adjacent ends being disposed in longitudinally spaced relation. A pintle pin 38 extends through the hinge barrel portions 32, 34 and 36 to effect the pivotal connection between the blades 28 and the drum 26.

20 Pivotal movement of the blades 28 in one direction is limited by connecting the hinge barrel portions 36 adjacent the inner ends of the blades 28 in such a manner that when the blades 28 are in their normal working or operative positions, the inner ends 40 thereof abut against the drum 26 to prevent rotation thereof in a clockwise direction beyond their respective operative positions, reference being made at this point to the full line position of the blade 28 illustrated in Figure 4.

25 The blades 28 are constantly biased for pivotal movement toward their respective operative positions by means of a substantially U-shaped spring 42. As is seen in Figures 3 and 4, the spring 42 includes a bight 44 from the ends of which extend a pair of laterally spaced arms 46, 48 which engage against the blades 28 and have portions thereof extending through the spaces between 30 the aforementioned adjacent ends of the hinge barrel portions 32, 34, 36 and around the pintle pin 38. The outer ends of the arms 46, 48 terminate in lateral extensions 46', 48' which bear against the hinge plate 50 utilized to secure the hinge barrel portions 32, 34 to the drum 26.

35 The above described hinge or pivotal connection between the blades 28 and the drum 26 permits the blades 28 to automatically feather in the face of storms by pivoting in a counter-clockwise direction against the tension of the springs 42, as is illustrated by the phantom lines shown in Figure 4.

40 An elongated drive shaft 52 has one of its ends fixedly secured within the impeller hub 22 for rotation with the impeller 12. The other end of the drive shaft 52 is journaled for rotation in a bearing 54 disposed in a boss 56 protruding from a substantially hollow gear box 58. The other end of the shaft 52 extends into the gear box 58 and has a hub 60 of a bevel gear 62 rigidly secured thereon.

45 The bevel gear 62 meshes with a bevel gear 64 disposed within the gear box 58, the gear 64 having a hub 66 rigidly secured to a driven shaft 68 adjacent the upper end thereof. The upper end of the shaft 68 is stabilized in a boss 70 which projects inwardly of the gear box 58, and the driven shaft 68 projects outwardly of the gear box 58 through a bearing 72 carried thereby, the shafts 52 and 68 being disposed at substantially right angles with respect to each other.

To effect the above described gear box assembly, the gear box housing 58 is split and is provided with pairs of forwardly projecting lugs 74, 76 geared together by bolts (not shown) and a pair of oppositely disposed spaced flanges 78, 80 between which is secured by conventional means one end of a weather vane 82. Said one end of said vane 82 follows the contour of adjacent portions of the gear box 58, and the lower forward corner thereof is connected to a collar 84 which surrounds an elongated substantially hollow tubular member 86 adjacent the upper end thereof.

The tubular member 86 surrounds the shaft 68 in spaced coaxial relation relative thereto, and the upper end thereof terminates in a radial flange 88 fixedly secured to the under side of the gear box housing 58 by bolts 90.

The member 86 extends downwardly through a truss collar 92 fixedly secured thereon by setscrews 94. The collar 92 seats on a thrust bearing 96 in which is journaled for rotation a portion of the member 86, and the bearing 96 has the lower side thereof abutting against the upper end of a boss 98 which is integral with and projects upwardly away from a bracket 100 that spans the ridgepole or ridgepiece (not shown) of the barn 16. The bracket 100 is provided with downwardly diverging arms 102, 104 which are preferably connected to the upper ends of a pair of oppositely disposed rafters 106, 108, respectively, by bolts 110 (see Figure 2) which pass through suitable openings 112 (see Figure 5). The tubular member 86 extends downwardly through a boss 114 formed in the bracket 100 and is journaled for rotation in a bearing 116 enclosed in a housing 118 having longitudinally extending oppositely disposed flanges 119, 120 connected by bolts 122 to a cross beam 124 extending transversely of the barn 16 and supported on a pair of opposed sides 126, 128 thereof.

The lower end of the tubular member 86 is externally threaded to receive thereon an internally threaded collar 130 having a radial flange 132, through which, at radially spaced intervals extend a plurality of bolts 134. The lower ends of the bolts 134 extend through suitable openings formed in the top wall 136 of the plenum chamber 20 and through the radial flange 138 of a substantially cylindrical housing 140 for a bearing 142 in which a lower portion of the shaft 68 is journaled. Nuts 144 maintain the assembly described in this immediate paragraph.

As is seen in Figures 2 and 3, the shaft 68 projects into the plenum chamber 20 and has secured to the lower end thereof the impeller 18. The plenum chamber 20 is provided with oppositely disposed vertically spaced air inlet and outlet ducts 146 and 148, respectively. It is important to note that the plenum chamber 20 is connected to the lower end of the tubular member 86 in such a manner that the outlet duct 148 faces in the same direction as the impeller 12.

Additional suspension means is provided for connecting the plenum chamber 20 to the tubular member 86. This means includes a split ring clamping member or collar 150 which extends around the tubular member 86 adjacent the lower end thereof. The terminal ends of the collar 150 are offset to provide ears 152, 154 through which extends a clamping bolt 156 secured by a clamping nut 158 (see Figure 6). The collar 150 is provided with a plurality of radially spaced apertured lugs 160 in which are connected the looped ends 162 of a plurality of struts 164, the other ends of which are connected with upwardly projecting hanger brackets 166 connected to the top wall 136 of the plenum chamber 20.

From the foregoing description it should now be manifest that wind impinging against the impeller blades 28 of the impeller 12 will effect rotation of the shaft 52 which, in turn, will rotate the bevel gear 62. The gear 64, as a consequence of the rotation of the gear 62, also rotates to drive the driven shaft 68. The shaft 68 now

being actuated will cause the impeller 18 of the plenum chamber 20 to rotate whereby air within the barn or edifice 16 is drawn through the inlet duct 146 and is discharged through the other duct 148 for impingement against a wall of the barn 16, wall 126, for example, against which the wind impinges. The wall 126 in the path of the wind is always the coldest and, consequently, the air occupying the space immediately adjacent thereto is at a lower temperature than the air occupying the remainder of the barn 16. However, with the incorporation of the present invention in any building or edifice such as the barn 16, the aforementioned cold air areas are substantially eliminated.

It will be understood that any change in the direction of the wind will cause the wind to impinge against the weather vane 82 at a new angle automatically causing the impeller 12, housing 58 and vane 82 to rotate into a new position with the impeller 12 again facing directly into the wind. Since the hollow tubular member 86 is rigidly connected to the gear box housing 58, the member 86 will also rotate, and this will rotatably change the position of the discharge duct 148.

Having described and illustrated in detail, one embodiment of this invention, it will be understood that the same is offered merely by way of example, and that this invention is to be limited only by the scope of the following appended claims.

What is claimed is:

1. Air distributing means for a building or edifice comprising a wind driven impeller, means rotatably supporting said impeller on the roof of said building and including an elongated substantially hollow tubular member rotatable with said impeller and extending into said building, a wind vane connected to and projecting laterally from said shaft adjacent said impeller, a plenum chamber disposed within said building and connected to said hollow tubular member for rotation therewith, said plenum chamber having an air discharge duct constantly facing in the same direction as said impeller and an oppositely disposed vertically spaced air inlet duct; an impeller disposed within said plenum chamber, and means connecting said first impeller in driving relation with respect to said second impeller.

2. Air distributing means for a building or edifice having a roof, a plenum chamber having air inlet and discharge ducts, said plenum chamber being disposed in said building and fixedly secured to one end of an elongated substantially hollow tubular member, the other end of said member extending through and projecting beyond said roof, means on said roof supporting said member for rotation about its longitudinal axis, a housing fixedly secured to said other end of said member for rotation therewith, a wind driven impeller mounted for rotation on said housing, a wind vane fixedly secured to said housing, said vane constantly tending to turn said wind driven impeller in such direction as to constantly face the wind, an impeller disposed within said plenum chamber, means connecting said first impeller in driving relation with respect to said second impeller, and said plenum chamber having vertically spaced air inlet and air discharge ducts.

3. Air distributing means for a building or edifice having a roof, as described in claim 2, wherein said wind driven impeller is fixedly secured on one end of an elongated shaft for rotation therewith, said shaft having the other end thereof projecting into said housing and journaled for rotation thereon, an elongated hollow tubular member having one of its ends fixedly secured to said housing for rotation therewith, the other end of said tubular member being fixedly secured to said plenum chamber to effect rotation thereof, a second shaft disposed within said tubular member in coaxial spaced relation relative with respect to said hollow tubular member, said second shaft having one of its ends fixedly secured to said second impeller and the other end thereof pro-

jecting into said housing, and a gear train disposed within said housing for connecting said first shaft in driving relation with said second shaft.

4. Air distributing means for a building or edifice having a roof, as defined in claim 3, wherein said wind driven impeller is provided with a plurality of blades hingedly connected thereto for pivotal movement in one direction, and resilient means on said impeller constantly biasing said blades for pivotal movement in the other direction, said pivotal movement of said blades occurring about an axis inclined at an acute angle relative to the axis of said first shaft.
